UNITED STATES PATENT OFFICE.

ULRICH SETH EBERHARDT, OF MAPLEWOOD, NEW JERSEY, ASSIGNOR TO NEWARK GEAR CUTTING MACHINE CO., OF NEWARK, NEW JERSEY, A CORPORATION OF NEW JERSEY.

RETAINING COLLAR.

1,408,993.

Specification of Letters Patent.

Patented Mar. 7, 1922.

Application filed July 25, 1919. Serial No. 313,348.

To all whom it may concern:

Be it known that I, ULRICH SETH EBERHARDT, a citizen of the United States, and a resident of Maplewood, in the county of 5 Essex and State of New Jersey, have invented certain new and useful Improvements in Retaining Collars, of which the following is a specification.

This invention relates, generally, to retaining collars, such as are used to hold gears or other machine elements from movement longitudinally of a shaft on which they are mounted, and particularly relates to means for positively securing the collar to the shaft 10 and at the same time providing for ready removal of the collar therefrom at the will of the operator.

It has been the practice heretofore in this art to hold retaining collars in place on the 20 shaft by the use either of split pins or nuts. This has given rise to more or less delay and difficulty in changing gears when the occasion arose; and it is one of the objects of this invention to avoid this difficulty 25 and to provide means allowing of the ready removal of the collar without the use of tools or other devices. Not only has the use of the collars heretofore employed given rise to difficulty in their removal, but it has also 30 been the occasion of considerable trouble resulting from the loosening and loss of the holding nut from its retaining position because of the vibration of the shaft on which the nut was mounted.

35 I have discovered that both difficulties referred to may be overcome by providing a retaining collar which can be locked into its retaining position and removed therefrom simply by the pressure or action of the fingers of the operator, and which collar at the 40 same time provides a much more efficient locking means than has heretofore been provided in the devices that have been known and used.

45 The preferred form of my invention consists in a retaining collar of the desired size which is provided with one or more movable locking members mounted in recesses formed for the purpose in the body thereof, such 50 locking members being accessible to the hand of the operator and normally held by a spring or equivalent means to their locking position in which they engage in a suitable recess or recesses formed on the surface of 55 the shaft on which the collar is mounted.

Preferably, the locking members extend across the length of the shaft in a direction substantially tangential thereto; and, in the preferred form, the locking members are moved along their own axes into and out of locking position. Other forms of the invention herein illustrated show locking members which, instead of being movable along their own lengths into and out of locking position, are turned about a pivot, the axis 60 of which may be placed either parallel with or transverse to the axis of the shaft on which the collar is used. In each form of the invention shown, I make use of the most prominent characteristics referred to in the 65 preferred form; that is, the locking member or members is movably mounted in the body portion of the collar member and adapted to be engaged by the fingers of the operator to be moved out of its locking position in a 70 recess formed in the shaft transverse to the length thereof.

The nature of the invention will be best understood when described in connection with the accompanying drawings, in which— 80

Fig. 1 is a vertical section of a preferred form of retaining collar embodying my invention and showing it in place on a shaft.

Fig. 2 is an end elevation of the retaining collar shown in Fig. 1.

Fig. 3 is a side elevation of the retaining collar shown in Fig. 1.

Fig. 4 shows, in two views, a side elevation and an end view of the form of locking pin used in the preferred form of the invention. 90

Fig. 5 is a view corresponding to Fig. 1, and showing a modified form of the invention.

Fig. 6 is an end elevation of the retaining collar shown in Fig. 5.

Fig. 7 is an end elevation of still another form of the invention, and shows the collar in place on a shaft.

Fig. 8 is a side elevation of the device shown in Fig. 7.

Fig. 9 is a transverse vertical section of still another form of the invention.

Fig. 10 is a side elevation of the form of the invention shown in Fig. 9.

Similar characters of reference designate 105 corresponding parts throughout the several views.

In the drawings, I have shown at 20 a portion of the frame-work of a suitable machine in which an enlarged portion 21 forms a 110

bearing for a shaft 22 on which a gear 23 may be mounted, and which it is desired to retain in place on the said shaft in manner to permit of its ready removal therefrom 5 when it is desired to change gears for any desired purpose. 24 designates the retaining collar embodying my invention, which, in this embodiment, is provided with locking pins 25 mounted to slide along their own 10 lengths in recesses 26 provided for the purpose in the collar 24 in a tangential relation to the central opening 27 in the collar, through which the shaft extends when the collar is placed thereon. Suitable springs 28, 15 normally urge the pins to their outermost positions in which shoulders 29 formed by notches 30 in the side of the pins, enter, preferably, opposite sides of a circumferential groove 31 formed in the shaft adjacent the 20 end thereof. In order to prevent the removal of the pins from their positions in the collar, notches 32 are provided in said pins with which stop pins 33 engage. In order to remove the collar from the shaft, it is 25 necessary merely for the operator to grasp the collar in one hand and exert the pressure of his fingers inwardly on opposite sides of the collar, to thereby press the outwardly extending ends of the locking pins 30 25 and force the locking shoulders 29 in opposite directions out of the locking groove 31. This unlocks the collar, and it can then be withdrawn from the shaft to permit the removal of the gear 23 or other member 35 which the retaining collar served to hold in place.

It will be noted that the outer extremities of the locking pins, which are engaged by the fingers of the operator, take the same 40 curvature as that of the periphery of the collar so that the operator is aware that, when he has placed the pins in a flush position with relation to the collar, the collar is in an unlocked position, and it is not necessary for him to see the collar in this operation, thereby facilitating the removal of the collars in situations where lighting is dim or lacking altogether.

I have found that the arrangement of the 50 locking pins in the particular form described greatly facilitates the operation of removing the collars. This arrangement naturally fits the hand of the operator and makes it a very simple matter to force the pins inwardly 55 against the pressure of the springs to their unlocking position. In other words, I have found that, by placing the pins in parallel relation to each other and in a tangential relation to the relatively small shaft member 60 22, the general effect is presented of pressing the pins inwardly in opposite radial directions with relation to the collar member, and this produces a very effective arrangement for the operation of the pins.

65 In another form of the invention, which

I have shown in Figs. 5 and 6, I make use of only a single locking pin 25 for holding the collar 24. The latter, in this embodiment, contains oiling means such as hole 34 arranged to have its inner end project into 70 an oil groove 35 formed longitudinally with relation to the end of the shaft member 36 on which this specific form of collar is used.

It will be seen that the shaft 36, instead of being provided with a circumferential 75 groove 31, as in Fig. 1, is supplied with merely a tangentially arranged groove 37 with which the shoulder 29 on the locking pin 25 engages to hold the collar in its locked position. The purpose of the groove 37 is 80 to determine the angular position of the collar 24 with relation to the shaft in order to bring the oil hole and oil groove in line.

In another embodiment shown in Figs. 85 7 and 8, instead of making use of the longitudinally slidable pins which have been shown in the figures already described, I employ a pivoted locking member which consists of a locking bar 38 pivoted on a pin 39 extending transversely of the collar and 90 longitudinally of the shaft on which the collar will be placed. In this form of the invention, a spring 40, bearing against the locking bar 38, preferably outside of the position of the pivot pin 39, serves to force the 95 locking end of the bar 38 into its position in the locking groove 31 of the shaft 22. The position of the pin in its locking position is substantially the same as that of the locking pins already referred to; and, in 100 this case also, one end of the locking member extends beyond the periphery of the retaining collar in a position to be engaged by the fingers of the operator to move the bar against the pressure of the spring 40 to 105 thereby unlock the collar and permit of its removal from the shaft.

In still another modification of the invention shown in Figs. 9 and 10, I show a locking pin 41 which is arranged to rotate about 110 its own axis into and out of locking position. A circumferential groove 42, provided near the inner end of the pin 41, is adapted to be engaged by a retaining pin 43 which serves to prevent the removal of the locking pin 115 from its position in the collar, and at the same time permits of the rotation of the pin about its axis. It will be seen that the position of the pin with relation to a shaft is such that the periphery of the shaft is intersected to a depth sufficient to afford a secure protection against movement of the collar longitudinally of the shaft; and, when in locking position, the pin is arranged to engage a groove formed in the shaft for the 120 purpose. In the position of the pin shown in Fig. 9, it will be seen that the same is disclosed in its locking relation; and, in order to move the pin to its unlocked position, it is necessary merely to grasp the 125 130

knurled thumb piece 44 and turn to a position where the concave or notched portion 30 is turned about to the side of the pin adjacent the shaft, whereupon the collar can 5 be instantly mounted or removed. In order to hold the pin in its locked and released positions, a small plunger pin 45 is mounted in a recess 46 formed in the collar in a direction transverse to the length of the locking 10 pin, so that the member 45 engages flat faces 47 formed in the locking pin in opposite sides thereof. A spring 48 interposed between the plunger pin 45 and a screw plug 49 serves to hold the plunger pin 45 in engagement 15 with the locking pin. This spring 48 is not sufficiently powerful, however, to prevent turning of the locking pin from either one of its alternative positions.

It will be seen that I have provided a retaining collar which can be easily placed in locking position and as easily removed therefrom, and that the means provided for holding the retaining collar in place afford a positive lock that absolutely prevents removal 25 of the collar from the shaft on which it is mounted, except by the willful act of the operator.

I claim:

1. A retaining collar, comprising: a collar 30 member arranged to be fitted to a shaft having a recess in the surface thereof, a movable locking member permanently retained in said collar under resilient control and adapted in its locking position to extend in a direction transverse the length of said shaft and into said recess, whereby longitudinal movement of the collar with relation to the shaft is prevented.

2. A retaining collar, comprising: a collar 40 member arranged to be fitted to a shaft having a recess in the surface thereof, a movable locking member permanently retained in said collar, resiliently actuated in the direction of the recess and adapted in its locking position to extend in a direction transverse the length of said shaft and into said recess, and a spring normally holding the locking member in its locked position.

3. A retaining collar, comprising: a collar 50 member arranged to be fitted to a shaft having a recess in the surface thereof, a movable locking pin permanently retained in said collar in a position tangentially intersecting the surface of said shaft and adapted in its locking position to extend into said recess, and a cut-out portion in said locking member whereby, when said locking member is moved along its axis to bring the cut-out portion into alignment with said shaft, the 55 collar may be removed from said shaft.

4. A retaining collar, comprising: a collar member arranged to be fitted to a shaft having a recess in the surface thereof, a movable locking pin permanently retained in said

collar in a position tangentially intersecting 60 the surface of said shaft and adapted in its locking position to extend into said recess, a cut-out portion in said locking member whereby, when said locking member is moved along its axis to bring the cut-out 70 portion into alignment with said shaft, the collar may be removed from said shaft, and a spring member normally holding said locking member in a position in which said cut-out portion is out of alignment with said 75 shaft to thereby lock the collar against movement with relation to said shaft.

5. A retaining collar, comprising: a collar member arranged to be fitted to a shaft having a circumferential groove in the surface 80 thereof, a pair of slideable locking pins permanently retained in said collar to engage the circumferential groove, said locking pins having extremities thereof projecting beyond the periphery of said collar and provided with cut-out grooves in the sides thereof, whereby said pins may be pressed inwardly by the fingers of the operator to bring the cut-out portions into alignment with said shaft to remove the pins out of 90 locking relation with the shaft and permit the removal of the collar.

6. A retaining collar, comprising: a collar member arranged to be fitted to a shaft having a circumferential groove in the surface 95 thereof, a pair of slideable locking pins permanently retained in said collar and arranged in a parallel relation to each other to engage the circumferential groove on opposite sides of said shaft, said locking pins 100 having extremities thereof projecting beyond the periphery of said collar and provided with cut-out grooves in the sides thereof, whereby said pins may be pressed inwardly by the fingers of the operator to 105 bring the cut-out portions into alignment with said shaft to remove the pins out of locking relation with the shaft and permit the removal of the collar.

7. A retaining collar, comprising: a collar 110 member arranged to be fitted to a shaft having a circumferential groove in the surface thereof, slideable locking pins permanently retained in said collar and arranged to engage said circumferential groove to lock 115 the collar against removal from said shaft, said pins extending in opposite directions beyond the periphery of said collar, whereby they may be manipulated by the fingers of the operator to remove the pins into unlocked 120 relation, and springs normally moving the pins into locking relation with said shaft.

Signed at Newark, in the county of Essex and State of New Jersey, this 21st day of 125 July, A. D. 1919.

ULRICH SETH EBERHARDT.
